UNITED STATES PATENT OFFICE.

AMELIA POTVIN, OF ALPENA, MICHIGAN.

SHOE-LACE TIP.

SPECIFICATION forming part of Letters Patent No. 766,520, dated August 2, 1904.

Application filed March 9, 1904. Serial No. 197,280. (No model.)

To all whom it may concern:

Be it known that I, AMELIA POTVIN, a citizen of the United States, residing at Alpena, in the county of Alpena and State of Michigan, have invented new and useful Improvements in Shoe-Lace Tips, of which the following is a specification.

This invention relates to shoe-lace tips, the object of the invention being to provide a simple and effective device of this character which can be easily made and applied to a lace, and the improvement is of such character that when applied it prevents the end of a lace from unraveling and is firmly held in position.

While I have termed my invention a "shoe-lace" tip, this should not be construed as a limitation, for the said tip can be used with equal facility in conjunction with other kinds of laces—for example, those used with corsets, girdles, belts, &c.

The improved tip, which is made from the material usually adopted in forming articles of this character, is provided with a longitudinal pin inserted into the fabric of the lace, the free end of the pin in the present instance pointing toward the corresponding end of the lace. Said pin is preferably upon a side of the tip, the opposite side of the tip, which when in use is of tubular form, overlying the pin to prevent unbending of the latter or its withdrawal from the lace.

I have selected for illustration in the accompanying drawings, forming a part of this specification, one convenient embodiment of the invention, which I will describe at length in the following description; but I do not limit myself to the disclosure thus made, as certain minor changes may be adopted within the scope of my invention set forth in the claims succeeding said description.

Referring to the drawings, Figure 1 is a perspective view of a lace-tip blank made in accordance with the invention. Fig. 2 is an elevation of one end of a lace, showing the manner of introducing the pin or tongue of the blank into the end of said lace. Fig. 3 is a longitudinal sectional elevation of the end of the lace and tip thereon in working relation.

Fig. 4 is a transverse sectional elevation of the lace-tip.

As previously indicated, the improved tip is formed of the material usually adopted in making devices of a similar character. The blank 2, from which the finished article is to be formed, may be stamped from a sheet of tin in some suitable way, the blank when stamped presenting a shape that is approximately a parallelogram. Concurrently with the stamping of the blank from a sheet of tin or similar material a longitudinal slit is formed along a side edge of the blank, thereby producing an elongated pin 3, or the blank may be slotted after it is stamped from its sheet, as may be found most expedient in practice. This pin is adapted to be introduced into the fabric of the lace 4 at the end of the latter. In the present case the pin is so introduced into the fabric that the free end of such pin will point toward the corresponding end of the lace, whereby when the tip is in its finished condition the possibility of the tip being pulled from the lace is exceedingly limited. After the pin is introduced into the lace I roll the blank 2 about the lace and in doing so bring that edge or side of the blank which is not provided with a pin over such pin. When so rolled, the blank makes the finished tip, which it will be found presents a tubular form and incloses the end of the lace, as well as houses and protects the pin 3, effectually preventing the latter from unbending and leaving the lace.

The tubular tip shaped from the blank 2 closely hugs the end of the lace, and pressure of a suitable nature can be utilized to bring about this result. It will be found that when the tip is applied to the lace it cannot, except under extraordinary conditions, be pulled therefrom, owing to the penetration of the lace by the pin constituting a part of the tip, while at the same time the body of the tip thoroughly protects the pin. The tip in addition to possessing the advantages pointed out also prevents unraveling of the lace. Preferably the free end of the pin 3 is pointed to insure its more ready insertion into a lace.

Having thus described the invention, what I claim is—

1. The combination of a lace and a tubular tip therefor, having a longitudinal pin along

one side thereof inserted into said lace and inclosed by the body of the tip.

2. The combination of a lace and a tubular tip therefor, having a longitudinal pin along one side thereof inserted into the lace and inclosed by the body of the tip, the free end of the pin pointing toward the corresponding end of the lace.

3. A blank for lace-tips, of substantially parallelogrammic form, slit near one edge to

form a pin, said edge forming one side of the pin, and the other side being formed by a wall of the slit.

In testimony whereof I have hereunto set my hand in presence of two subscribing witnesses.

AMELIA POTVIN.
